9 Claims. (Cl. 214—654)

This invention relates to an improved stabilizer attachment, and more particularly pertains to a stabilizer adapted for use with fork lift trucks.

In many industries, notably the soft drink industry, in which stacked cases of bottles are moved about a plant, breakage has become a serious and expensive problem. With the increasing use of automatic bottling and bottle-handling equipment, it became essential for stacked cases of bottles, both empty and filled, to be rapidly and continuously moved to keep pace with filling, washing and other automatic bottle-processing devices.

The necessitated increased bottle movement resulted in increased breakage, particularly in those instances in which manpower and time were not available to allow "tying in" or staggered stacking of the rectangular cases of soft drink bottles on a pallet. Upon being engaged and moved by a fork lift truck, cases oftentimes fell from the pallet as the lift trucks turned corners, even at comparatively low speeds, as a result of centrifugal forces acting on the cases.

It is an object, therefore, of this invention to provide a novel stabilizer construction which may readily be attached to a fork lift truck of ordinary construction without the necessity of significantly altering such truck construction.

It is another object of this invention to provide a stabilizer for use with a fork lift truck which is composed of a minimum number of sturdy, inexpensive parts having low initial cost.

It is a further object of this invention to provide a stabilizer attachment in which the major working components thereof may readily be detached from a fork lift truck if such truck is to be used for purposes in which the stabilizer is not necessary.

It is another object of this invention to provide a stabilizer attachment which after an initial visual aligning operation automatically comes into play in the normal course of engagement of a pallet containing stacked goods by a fork lift truck.

The above and other objects will become more apparent from the following detailed description when read in the light of the accompanying drawing and appended claims.

In one embodiment of the stabilizer provided by this invention a transverse support having slotted, upwardly extending plate portions defining opposed end limits thereof is welded, bolted or otherwise suitably affixed to the upper surface of a transverse brace of a fork lift truck lifting frame. The opposed slotted plates are traversed by a transverse axle member and, accordingly, serve as spaced bearings therefor. The axle member is resiliently biased in a downwardly direction, so as to be urged into engagement with the lower end limits of the slotted bearings by means of at least one coil spring or equivalent means connected to the axle at one end limit and anchored to an underlying lift truck frame portion at the other.

Secured to opposed end limits of the axle are socket connector means which are adapted to receive end portions of stabilizer arm members. The stabilizer arms are retained in a slightly upwardly inclined position by means of spring members which engage the arms and oppose downward pivotal movement thereof about the axle to which connected. The anchoring end of each

2

spring may be attached to an upper end limit of one of the axle slotted bearings.

Depending from a portion of each stabilizer arm at a point spaced adjacent the end portion thereof which engages the axle socket connector is an actuator arm. Each actuator arm may have an offset end portion disposed away from the fork lift truck on which supported.

In the normal course of stabilizer operation a fork lift truck in the course of engaging a pallet, on which 10 cases of bottles are stacked, forces the depending actuator arms of the stabilizer into engagement with the cases. Concomitantly the stabilizer arms are pivoted against the tension in their supporting springs into engagement with spaced portions of the uppermost stacked cases 15 which are then resiliently locked to the truck, as will hereinafter be explained in greater detail.

For a more complete understanding of this invention reference is now made to the drawing wherein:

FIG. 1 is a fragmentary side elevational view 20 illustrating a fork lift truck, having the stabilizer of this invention mounted thereon, in the process of engaging a pallet on which cases of bottles are stacked;

FIG. 2 is similar to FIG. 1 and illustrates the fork lift truck and stabilizer of FIG. 1 after the pallet and 25 stacked cases thereon have been securely engaged;

FIG. 3 is a fragmentary enlarged perspective view of the stabilizer of this invention and a portion of a fork lift truck to which it is secured;

FIG. 4 is an enlarged perspective view of a transverse 30 section of a socket connector employed in the stabilizer attachment of FIG. 3; and

FIG. 5 is a fragmentary, exploded, perspective view of one embodiment of a stabilizer attachment constructed in accordance with the teachings of this invention.

Referring now particularly to FIG. 3, one embodiment 35 of a stabilizer for a fork lift truck is illustrated, together with a fragmentary portion of a lift truck to which the stabilizer is attached. It will be understood that provided stabilizer 10 is adapted to be employed with fork lift trucks of conventional construction. The stabilizer 10 does not require any significant structural changes in the lift truck in the course of attaching a stabilizer thereto.

The portions of a lift truck illustrated in FIG. 3 comprise extensible vertical guide standards 12 over which a 45 lifting frame 14, composed in part of vertical bars 16, reciprocally slidably moves as a load engaged by a fork member of the lift truck is raised or lowered. The lifting frame 14 may also be laterally adjustable relative to the guide standards 12; such movement is permissible with many conventional lift truck constructions.

The stabilizer attachment embodiment illustrated in the drawing comprises a transverse base channel 18 integrally formed at opposed end portions with vertical slotted plates 20. Plates 20 function as bearings for a rotatable 50 axle 22, more clearly seen in FIG. 5, which traverses slots 24 formed in the opposed bearing plates.

Integral channel base-bearing plate assembly 25 may be secured to upper transverse strip 15 of the truck lifting frame 14 by welding or the use of bolts and nuts, such as bolt 28 and nut 31 illustrated in the exploded view 60 of FIG. 5. The use of a nut and bolt assembly obviously allows the stabilizer attachment assembly 10 to be readily removed from a fork lift truck when desired.

Welded or otherwise suitably affixed to opposed end 65 portions of axle 22 are socket connectors 30, one of which is more clearly seen in section in FIG. 4. The socket connectors 30 are disposed at substantially right angles to the axis of rotation of axle 22. They are recessed at 32 (see FIG. 4) and welded or otherwise suitably affixed to end portions of the axle 22.

Each socket connector 30 has a central bore 34, more clearly seen in FIG. 4. The end portion of the bore 34

connected with the distal end of the socket connector communicates with a downwardly extending slot 36, which is of substantially the same width as the bore diameter. In addition, inclined slot or keyway 38 is formed in an upper peripheral portion of the connector 30 which is disposed in a central longitudinal plane of the connector. Accordingly, slot 38 is formed directly above the central longitudinal axis of the connector 30.

It is the function of each socket connector 30 to engage a discrete arm assembly 40, one of which is fragmentarily illustrated in FIG. 5. Each arm assembly 40 comprises a stabilizer arm 42 having a relatively downwardly inclined distal end portion 42a (see FIG. 3) in the normal position of assembly. Arm 42 is integrally formed in substantially right angle relationship with an actuating arm 44 having an offset terminal end portion 44a. The latter actuating arm portion is disposed substantially parallel with arm portion 44c joined to stabilizer arm 42 and connected therewith by means of a diagonally connecting arm portion 44b. The arm assembly 40 may be readily engaged with the connector 30 by inserting distal end portion 46 (see FIG. 5) of each stabilizer arm 42 into the bore 34 of the socket 30 until the terminal end of arm portion 46 engages stop wall 50 of socket 30, more clearly seen in FIG. 4. Stabilizer arm portion 46 is only able to engage stop wall 50 if actuator arm 44 is allowed to traverse slot 36 of the connector 30.

In the course of effecting this interfitting connection, angularly inclined terminal portion 54a (see FIG. 5) of each spring adjusting strip 54 will be received within the keyway 38 of the socket 30 and interlock therewith in the manner illustrated more clearly in FIG. 3. It is apparent that the interfitting of the spring adjusting strip 54 with the connector keyway 38 and the disposition of depending actuator arm 44 within the slot portion 36 of the connector 30 will prevent relative rotatable movement between each arm assembly 40 and engaged connector 30 when in interlocking engagement.

As will be more clearly seen from FIG. 3, the means retaining each arm assembly 40 in interlocking engagement with socket connectors 30 comprise coil springs 58, which engage an anchor aperture 60 disposed in an anchor strip 62, more clearly seen in FIGS. 3 and 5, at one end limit. Springs 58 engage that aperture formed in adjusting strip 54 of each arm assembly 40, which enables the arm assembly and connected axle 22 to be disposed with the stabilizer arms in a slightly upwardly inclined position in the manner illustrated in FIG. 3.

The stabilizer arm assemblies 40 and interconnecting axle and socket connector assembly move as a unit in the normal course of operation of the stabilizer attachment 10. It is also seen from the foregoing description that each coil spring 58 performs the dual function of positioning the stabilizer arm assemblies, as well as exerting an axial force on stabilizer arm portions 46, urging the same into engagement with stop wall portions 50 of each socket connector 30.

Although the arm assemblies and interconnecting axle 22 may move upwardly when an upwardly directed force is imparted thereto because of the slotted bearing plates 20, the arm assemblies and interconnecting axle are normally disposed in a condition of nonuse at the lowermost portion of the bearing slots in the manner illustrated in FIG. 3. The stabilizer arms and axle assembly are urged continuously into the position illustrated in FIG. 3 by means of coil springs 68.

As is more clearly seen from the exploded view of FIG. 5, coil springs 68 are secured at their upper distal end limits to axle 22 and are provided with elongate stems 68a which traverse apertures appropriately disposed in the base channel 18. It will be noted from FIG. 3 that each coil spring 68 is detachably secured at an opposed lower distal end limit to one of the lifting frame vertical members 16. It is thus apparent that the stabilizer arm and axle assembly is resiliently down-

wardly urged so that the axle 22 engages the lower end limits of slots 24 formed in the spaced bearing plates 20.

In the normal course of stabilizer operation, a fork lift truck engages a pallet, such as pallet 70 in FIGS. 1 and 2, by means of a fork 72 disposed beneath lifting frame 14. In the course of pallet engagement, offset terminal end portion 44a of each actuator arm 44 will engage a side surface portion of a stacked case or cases, in the manner illustrated in FIGS. 1 and 2, as the lifting frame 14 approaches the stacked cases. Because of the connectors 30, the actuator arms may be disposed forward of frame 14, as illustrated.

The number of cases 74 stacked at the pallet 70 define a height, together with the pallet, which is greater than the level at which the axle 22 of the stabilizer attachment 10 is disposed when the lift truck is in the process of engaging the stacked cases in the manner illustrated in FIG. 1.

Accordingly, as the fork lift truck continues to approach the stacked cases, the actuator arms 44 pivotally move each stabilizer arm 42 downwardly between two rows of aligned bottles. It will be noted from FIG. 3 that cut out portions 17 in lifting frame strip 15 are provided. Cut outs 17 are in alignment with the actuator arms 44 whereby said latter arms may move behind the case-engaging face of the lifting frame in the manner illustrated in FIG. 2 after the lift fork truck has completely engaged the pallet.

As previously mentioned, quite often lifting frames, such as frames 14 illustrated in FIG. 3, are laterally adjustable so that an operator may align the stabilizer arms 42 with a valley defined by two rows of bottles prior to moving his fork lift truck into engagement with a pallet on which a number of stacked cases are disposed. If an operator initially approaches the pallet and cases properly, lateral adjustment of the frame 14 and arms 42 is not necessary. The interval between the arms 42 is, of course, predeterminedly set so that they may each lie in a bottle valley upon pallet-truck engagement.

Since the height of the uppermost case is greater than the plane in which axle 22 is disposed, the latter axle is forced to move upwardly in slotted bearings 20. It will at this time be noted that slots 24 in the plates 20 are upwardly inclined in a direction away from the stacked cases to facilitate the upward movement of the axle and arm assemblies. If the slots 24 are sufficiently long a stabilizer construction may be enabled to handle stacks of cases of different heights. The slotted bearings of the provided stabilizer thus inherently provide flexibility in the course of stabilizer use.

It is seen, therefore, that as the fork lift truck engages a pallet of stacked goods in the manner illustrated in FIGS. 1 and 2, in the manner well known, the stabilizer 10 has the actuator arm portion thereof urged into engagement with the stacked cases, thereby forcing the stabilizer arms to pivot downwardly into tight engagement with the uppermost cases 74. The downwardly disposed terminal ends 42a of the stabilizer arms are able to readily engage portions of the cases disposed furthest from the stabilizer, as illustrated on FIG. 2, as the latter arms assume the downwardly disposed position illustrated. Obviously as the axle 22 proceeds upwardly within the slots 24 of the plates 20, coil springs 68 are extended creating a tension tending to return the axle to the lowermost position with the bearing slots 24. Such tension is greater than that normally exerted on the axle in the position of stabilizer rest illustrated in FIG. 3.

With the stacked cases in the stabilizer-engaged position of FIG. 2, the engaged pallet and cases thereon may be tilted and the lifting frame 14 of the lift truck may be raised. The pallet and stacked cases may then be rapidly transported in safety to a desired destination. Because of the compression forces exerted between the stacked cases by virtue of the stabilizer arms 42, there will be no danger of the cases falling from the pallet, as the pallet

and cases turn corners on the supporting truck fork 72. The stabilizer arm disposition between projecting bottles or cartons in which the bottles are disposed assists the compression forces exerted by spring 68 in retaining the cases to the pallet 70.

Release of the stabilizer attachment from the stacked cases automatically occurs when the fork of the fork lift truck is withdrawn from its engagement with the pallet 70. After the pallet 70 is placed upon the ground or a truck floor or any other supporting surface, the fork lift truck is backed away from the stacked cases and the weight of the cases enables the resiliently engaging stabilizer arms 42 to slidably disengage from the upper cases 74. Disengagement obviously becomes progressively easier upon truck withdrawal since as soon as the fork lift truck backs away from the stacked lifted cases, actuator arms 42 no longer engage the cases. The stabilizer arms are thus enabled to pivot out of engagement with the cases, which pivotal movement is caused by the coil springs 58.

It should at this time be noted that the downwardly disposed terminal end portions 42a of the stabilizer arms facilitate loading and unloading of stacked cases within a truck wherein there is very little overhead clearance for insertion and withdrawal of the stabilizer arms.

It is apparent, therefore, from the foregoing that a novel stabilizer assembly of simple design has been presented which may be readily attached to a fork lift truck construction of substantially any manufacture. As previously mentioned, the entire stabilizer assembly may be removed from a lift truck if desired, if the same is secured to such truck by means of a nut and bolt assembly.

It is also possible, however, to weld the channel and bearing plate assembly 25 to a lifting frame strip, such as strip 15 illustrated in FIG. 3. When it is desired to employ the fork lift truck for uses not requiring a welded-on stabilizer assembly, the portions of the assembly 10, other than the base and bearing plates, may be removed. Removal is effected by withdrawing screw members 80, more clearly seen in FIG. 5, whereby locking plate 82 and spring anchor 62, may be removed; axle 22 may then be readily withdrawn. Springs 68 are detached from their engagement with vertical members 16 of the lifting frame prior to such axle removal.

In view of the above description of the provided stabilizer assembly, it is apparent that many modifications may be made therein and the resulting constructions will still fall within the scope of the invention disclosed. It is apparent, for instance, that the stabilizer arms and actuator arms need not be integrally formed, but each may be separately attachable to the axle 22; or, the arms may be integrally formed with the axle. The number of stabilizer arms or actuator arms is not critical and only an appropriate number is necessary to serve a specific purpose. For instance, in the event that stacked goods having a planar upper surface were to be moved by a lift truck employing the above-described stabilizer, a single stabilizer arm in some instances would be adequate for retaining all of the stacked goods in proper position.

The above-described stabilizer assembly is obviously simple in design, inasmuch as it is intended that the stabilizer arms, axle and actuator arms all move as a unit. The minimum number of moving portions greatly reduces the chances for malfunctioning.

It is intended that this invention be limited only by the scope of the pending claims.

We claim:

1. A stabilizer for a load comprising transverse rotatably movable axle means, opposed bearing means adapted to supportably engage opposed end portions of said axle means and allow said axle means to upwardly move relative thereto so as to allow said axle means to automatically accommodate itself to slight differences in the height of the load, outwardly extending, upwardly inclined arm means connected to said axle means, and actuator means secured to said axle means adapted to

pivotal move said axle means upon movement of said actuator means so as to urge upwardly inclined arm means toward a horizontal position; said axle means, arm means and actuator means being so interconnected as to move as an integral unit whereby pivotal movement of said actuator means through an angle pivotally moves said arm means through an equal angle of rotation about said axle means.

2. A stabilizer comprising axle means, at least one stabilizer arm extending from said rotatable axle means, actuator means connected to said axle means adapted to rotatably move said axle means and stabilizer arm upon movement thereof, bearing means engaging spaced portions of said axle means adapted to supportably engage said axle means and enable said axle means to resiliently move in an upwardly direction relative thereto upon imparting of an upwardly moving force to said axle means, and means urging said axle means into a predetermined position relative to said bearing means so as to resiliently oppose any upwardly moving force imparted to said axle means.

3. The stabilizer of claim 2 in which said bearing means comprise vertically disposed, slotted plates in which the slots are upwardly inclined in a direction oppositely disposed to the direction of extension of said stabilizer arm from said axle means.

4. The stabilizer of claim 2 in combination with means connected to said stabilizer arm adapted to position said arm in a predetermined position relative to the horizontal plane, said positioning means resiliently opposing downward pivotal movement of said stabilizer arm.

5. A stabilizer comprising a transverse support means having spaced, slotted, upwardly extending portions; transverse axle means traversing said support means slotted portions and adapted to rotatably move relative thereto, at least one actuator means connected to and depending from said transverse axle means, upwardly inclined arm means angularly disposed to said axle means secured to spaced portions of said axle means, and means connected to said axle means biasing said axle means into the lowermost portions of the slotted portions of said support means, said axle being movable along the length of the slots of said stabilizer support means in opposition to the biasing means; said upwardly inclined arm means and depending actuator means moving as a unit in the normal course of stabilizer operation.

6. In a stabilizer construction, spaced arm assemblies, each of said assemblies comprising elongate stabilizer and actuator arm means disposed in substantially right angle relationship, a rotatably movable axle means adapted to detachably engage each of said spaced arm assemblies whereby said arm means are radially disposed of said axle means, means connected to said arm assemblies for positioning said stabilizer arm means in a predetermined position, bearing means engaging spaced portions of said axle means enabling said axle means and engaged arm assemblies to upwardly move upon the imparting of an upward force to said assemblies, and resilient biasing means connected to said axle means urging said axle means in a downwardly direction.

7. A stabilizer comprising a transverse rotatably movable axle means, spaced slotted bearing means engaging spaced portions of said axle means, the bearing slots extending in vertical planes whereby said axle means may move upwardly relative to said bearings upon imparting a force moving in an upward direction thereto, connector means secured to spaced portions of said axle means, stabilizer arm means adapted to be inserted in interfitting engagement with said connector means, means connected to said stabilizer arm means resiliently urging said latter arm means into interfitting engagement with said connector means and positioning said latter arm means in an upwardly inclined position, actuator arm means connected to said axle means and depending therefrom, and means resiliently urging said axle means downwardly into

the lowermost portion of said bearing slots; said stabilizer arm and actuator arm means moving as a unit in the normal course of stabilizer operation.

8. A stabilizer comprising a rotatably movable axle means, opposed slotted bearing means adapted to supportably engage opposed end portions of said axle means and enable said axle means to upwardly move relative thereto upon the imparting of forces having an upward direction to said axle means, outwardly extending arm means radiating from said axle means movable in substantially the vertical plane, first resilient means connected to said outwardly extending arm means adapted to locate said arm means in a plane inclined to the horizontal and oppose downward pivotal movement of said outwardly extending arm means in a downward direction, depending actuator means radiating from said axle means adapted to rotatably move said axle means to which connected upon the imparting thereto of a force moving

5
10
15

substantially in the horizontal plane, and second resilient means connected to said axle means biasing said axle means into the lowermost position within said slotted bearing means.

9. The stabilizer of claim 8 in which the distal terminal end portions of the stabilizer arm means are downwardly inclined relative to the proximal portion thereof and said actuator means comprises at least one arm depending from said axle means having a distal terminal portion offset in the direction of the terminal end portions of said stabilizer arm means.
